CLAIM

The ornamental design for a watch dial, as shown and described.

DESCRIPTION

FIG. 1 is a front elevational view of a watch dial showing my new design;

FIG. 2 is a left side elevational view;

FIG. 3 is a right side elevational view;

FIG. 4 is a rear elevational view;

FIG. 5 is a top plan view;

FIG. 6 is a bottom plan view;

FIG. 7 is a bottom, front and right side perspective view, the watch case and strap are shown in dotted line for environmental purposes only and form no part of the claimed design;

FIG. 8 is a front elevational view of a second embodiment of my new design of FIGS. 1-7;

FIG. 9 is a left side elevational view;

FIG. 10 is a right side elevational view;

FIG. 11 is a rear elevational view;

FIG. 12 is a top plan view;

FIG. 13 is a bottom plan view; and,

FIG. 14 is a bottom, front and right side perspective view thereof, the watch case and strap are shown in dotted line for environmental purposes only and form no part of the claimed design.

FIGS. 2, 3, 5, 6, 9, 10, 12 and 13 are all drawn on an enlarged scale.
